UNITED STATES PATENT OFFICE.

WORTH R. BARRINGER, OF DENVER, COLORADO, ASSIGNOR TO THE PUBLIC SAFETY DEVICE COMPANY, OF DENVER, COLORADO, A CORPORATION OF COLORADO.

GUARD FOR BOTTLE-CORKS.

1,243,916.

Specification of Letters Patent. Patented Oct. 23, 1917.

Application filed February 16, 1917. Serial No. 149,095.

To all whom it may concern:

Be it known that I, WORTH R. BARRINGER, a citizen of the United States, residing at Denver, in the county of Denver and State 5 of Colorado, have invented certain new and useful Improvements in Guards for Bottle-Corks, of which the following is a specification, reference being had to the accompanying drawings.

10 This invention relates to an improved guard for bottle corks and has for its primary object to provide a simple and inexpensive guard attachment for bottles which will prevent the cork being withdrawn by 15 children, or by adults unintentionally when the contents of the bottle are of a poisonous nature.

It is another object of my invention to provide a device of the above character constructed from a single piece of sheet metal which may be easily applied to or removed from a bottle of conventional form.

It is a more particular object of the invention to provide a bottle cork guard 25 formed from sheet metal and including a split annular band to clampingly engage around the bottle neck and one or more guard fingers projecting from one edge of the band and adapted to be bent around the 30 beaded edge of the bottle neck and downwardly upon the cork, the terminals of the fingers being pointed and angularly bent to project above the cork.

And it is a further general object of the 35 invention to provide a device for the above purpose which may be inexpensively manufactured, may be repeatedly used on bottles of various sizes, and is very serviceable and convenient for the purpose in view.

40 With the above and other objects in view, my invention consists in the novel features of construction, combination and arrangement of parts to be hereinafter more fully described, claimed and illustrated in the accompanying drawing, in which,

Figure 1 is a perspective view showing one embodiment of my invention applied to the neck of a bottle;

Fig. 2 is a top plan view;

50 Fig. 3 is a plan view of the guard before application to the bottle;

Fig. 4 is a perspective view showing a slightly modified form of the device; and

55 Fig. 5 is a detail plan view of the latter construction.

Referring in detail to the drawing and more particularly to Figs. 1, 2 and 3 thereof, B designates the bottle having a neck N in which a cork or stopper C of conventional form, is adapted to be inserted.

60 My improved guard device is cut or stamped from a piece of sheet metal to provide a resilient body strip or plate 5 adapted to be bent into substantially circular form and having its terminal portions angularly disposed and outwardly extended in parallel relation to each other, as at 6. Upon one edge of this metal band, in spaced relation to its opposite ends, the elongated, tapering fingers 7 are formed.

70 When the device is first applied to a bottle, the metal strip or band 5 is engaged upon one side of the bottle neck N and bent around the same into close contact therewith and with the fingers 7 projecting upwardly above the upper edge of the bottle neck. These fingers are then bent around the bead on the upper edge of the bottle neck, as shown at 8, and the pointed terminals of the fingers, indicated at 9, are angularly bent to project above the cork. It

75 will thus be apparent that should the bottle be placed upon a shelf with numerous other bottles containing non-poisonous materials, the poison containing bottle equipped with the guard will not be accidentally removed and the cork extracted without warning. The upwardly projecting points 9 of the guard fingers will prick the fingers of the

80 hand when an attempt is made to withdraw 90 the cork, thus warning the person of the dangerous character of the contents of the bottle.

85 In Figs. 4 and 5 of the drawing, I have shown a slightly modified form of the device wherein the metal strip or band 5' is centrally provided with a single guard finger 7' to be bent over and upon the cork in the manner above described. The terminal 9' of this finger which is sharply 95 pointed, is curved or bent outwardly at the center of the cork and will operate in a like manner to the first described form of the device to prevent the accidental removal of the cork from the bottle.

100 105 From the foregoing description, taken in connection with the accompanying drawing, the construction and manner of use of my improved bottle cork guard will be clearly and fully understood. As the guard 110

is constructed from a single piece of sheet metal, it will be manifest that the same can be manufactured in large quantities at comparatively small cost so that the device can 5 be used for advertising purposes. The improved guard may, however, be separately sold in the form illustrated in Figs. 3 and 5 of the drawing and readily applied to the bottle by the individual purchaser. After 10 the contents of the bottle have been consumed, the guard device may be readily removed and applied to another bottle.

While I have herein shown and described the preferred construction and arrangement 15 of the several parts of the device, it is to be understood that the device is susceptible of considerable modification and I, therefore, reserve the privilege of adopting all such legitimate changes as may be fairly embodied within the spirit and scope of the invention as claimed.

Having thus fully described my invention, what I desire to claim and secure by Letters Patent is:

25 1. A bottle cork guard formed from a sin-

gle piece of sheet metal and including a band adapted to extend around and clampingly engage a bottle neck, said band being provided with a guard finger extending from one edge thereof and of such a length as to overlie the outer end of a cork inserted in the bottle neck and to have its free terminal extend outwardly from the cork. 30

2. A bottle cork guard formed from a single piece of sheet metal and including a band adapted to extend around and clampingly engage a bottle neck, said band being provided with fingers extending from one edge thereof and of a length to overlie the outer end of a cork, said fingers being so 35 spaced one from the other as to be substantially diametrically opposed when the guard is in applied position. 40

In testimony whereof I hereunto affix my signature in the presence of two witnesses. 45

WORTH R. BARRINGER.
